CRATE FOR MILK BOTTLES OR THE LIKE

Houston Rehrig, Pasadena, Calif., assignor to Rehrig Pacific Company, Los Angeles, Calif., a corporation of California

Continuation-in-part of design application Ser. No. 12,986, Aug. 1, 1968. This application Apr. 30, 1969, Ser. No. 16,954

Term of patent 14 years

Int. Cl. D9—04

U.S. Cl. D9—177

FIG. 1

FIG. 2

FIG.3

FIG.4

FIG5

FIG. 1 is a front perspective view of a crate for milk bottles or the like showing my new design;

FIG. 2 is an end elevation view thereof on an enlarged scale, the other end being identical thereto;

FIG. 3 is a side elevation view thereof, the other side being identical thereto;

FIG. 4 is a top plan view thereof; and

FIG. 5 is a sectional view thereof, in elevation.

This is a continuation-in-part of design application Ser. No. 12,986, filed Aug. 1, 1968 and now abandoned.

I claim:

The ornamental design for a crate for milk bottles or the like, substantially as shown and described.
